CLAIM

The ornamental design for a beverage container, as shown and described.

DESCRIPTION

FIG. 1 is a front perspective view of my new design for a beverage container;

FIG. 2 is a front elevation view thereof;

FIG. 3 is a rear elevation view thereof;

FIG. 4 is left side elevation view thereof;

FIG. 5 is a right side elevation view thereof;

FIG. 6 is a top plan view thereof;

FIG. 7 is a bottom plan view thereof;

FIG. 8 is another front perspective view thereof shown with a lid for clarity of disclosure; and,

FIG. 9 is another top plan view thereof shown with a lid for clarity of disclosure.

The broken lines depict portions of the beverage container that form no part of the claimed design.

1 Claim, 9 Drawing Sheets
